CHARLES MARTIN BAGSHAW, OF LEICESTER, ENGLAND.

TACK-SUPPLYING APPARATUS FOR NAILING MACHINES.

Application filed July 11, 1924, Serial No. 725,358, and in Great Britain July 12, 1923.

This invention has reference to improvements in and relating to apparatus for supplying tacks to a nailing machine by which a number of tacks may be driven simultaneously into the work.

By the use of some machines it is possible for certain kinds of work to drive a plurality of tacks of one sort, and for other kinds of work a plurality of tacks of another sort. For instance in boot and shoe manufacture, tacks of different lengths are driven to secure a pulled over upper accordingly whether welt or McKay shoes are being made.

In apparatus heretofore in use for supplying a plurality of tacks of either of two different lengths, to be driven simultaneously, each tack-pot has a plurality of tack raceways and from each raceway a single tack is taken by means of a plurality of simultaneously operated separators (one separator being located at the end of each raceway) for each complete revolution of the machine.

Such an apparatus is not only cumbered with a considerable amount of mechanism essential to its working, but is, further, defective in that if a single tack becomes jammed all the separators are thrown out of action and no tacks at all are delivered.

In my British Patent No. 175,691, I disclosed an apparatus for supplying a plurality of tacks from a single tack-pot to be driven simultaneously. In this apparatus there is but one raceway and a single separator which is actuated a number of times—according to the number of tacks required to be driven simultaneously. Not only is this apparatus comparatively simple but should a tack become jammed there will be only one tack missing from the work, and this can easily be rectified by the workman. As a result of experiments I have succeeded in constructing an apparatus, to operate to some extent on the same principle as that of my former apparatus which apparatus forms an important feature of my invention and, whereby not only a number of either of two particular lengths of tacks may be supplied, but which apparatus will be efficient for a greater range of tacks, that is to say not only tacks of a greater range of different lengths but also having shanks of different thickness, and so that whatever their lengths the tacks will be inverted. It must be borne in mind it is of the utmost importance that complexity of

apparatus to attain these results should be avoided.

Additional to the foregoing my invention also comprehends improved means for actuating the separator; improved means for actuating the tack delivery means; an improved inner raceway; means for maintaining the inner raceway connected up with a movable outer raceway; means for putting the clearer into and out of operation; and the combination of two or more of the said means.

In the accompanying drawing a preferred constructional form of my improved apparatus suitable for two lengths or sizes of tacks is diagrammatically illustrated, Fig. 1 being a side elevation, Fig. 2 a front view of the apparatus, Fig. 3 a plan view of a detail to be referred to, Fig. 4 a section through the hoppers showing in more detail the raceway construction, and Fig. 5 the raceways leading from the hoppers.

In said drawing F denotes a frame of suitable form which carries two rotary tack-pots 8, 9 both of which are secured on a shaft 10 to which rotary motion is imparted by a worm gear 11 on a shaft 12 which carries a driving pulley 13.

Mounting both tack-drums on one shaft so that both are continuously rotated is much more simple and generally efficient—especially having regard to the improvements herein-after to be described—than to mount them on separate shafts and provide clutch mechanism whereby the desired tack-drum will be put in gear and the other out of gear with the driving mechanism.

Supported by the machine frame and pivoted on a pin 14 that is located as near as conveniently possible to and midway of the drums 8 and 9 is an inclined raceway block 15 that is provided with two converging raceways 16, 17, one for each tack-drum. At the lower end of the raceway block is a separator 18 that is to be reciprocated as will be described and with which either of the raceways 16, 17, may be connected up.

Within each tack drum there is the usual raceway 20 (21) but in accordance with my invention the raceway is supported so as to be movable in the longitudinal direction (for instance by being supported on a slideway) and they are respectively connected by springs 22, 23, with the outer raceways 16, 17, so that the said inner and outer raceways are 110

at all times maintained in contact and consequently there is not at any time space between them wherein, as heretofore has been the case, tacks may become jammed.

5 Each inner raceway may have the usual clearer 24 carried on a rock shaft 25 on which is mounted a sort of collar 26 having a lug 31 projecting from it with which the cam blocks 32 on the tack-drum contact to rock

10 the clearer as is well understood.

In accordance with my invention only one of the clearers is to be in operation at any time, and for this purpose the clearers are mounted on separate shafts 25 and 50, and 15 means are provided whereby the workman may throw into operation the particular clearer that is required to be active and to throw out of operation the other clearer.

In order that the operator shall not 20 require to exercise special care to put into operation the appropriate or relevant clearer and to throw out of action the clearer that it not, for the time being, required, my invention further comprises means whereby the

25 putting into and out of operation of the clearers is effected automatically by means that are dependent for their operation on the throwing into communication with the separator any one or other of the raceways 16, 17, 30 according to the length or size of tacks it is intended to employ.

To this end I provide—by way of example—the following mechanism:

Mounted on a suitable part of the frame is 35 a stud 34, on which is secured a hand lever 38 which is intended to be put in either of the positions shown (in Fig. 3) in full and broken lines respectively thereby to rotate the stud 34 through an angle of 180 degrees.

40 Also attached to the stud is an eccentric 35, the strap 36 of which has a stem 37, having at its free end an eye or collar to engage a stud 33 on the lower face of the raceway block 15, the arrangement being such that 45 when the hand lever 38 is in the position, shown in full lines in Fig. 3, the raceway 16 is in communication with the separator 18, whereas when it is in the position shown in broken lines the raceway 17 is in such communication.

Additional to the eccentric 35, there is secured to the stud 34 an eccentric 39 the strap 40 of which has a link 41 that is connected to the free end of a lever 42 mounted on a suitably supported shaft 43. Said shaft also carries a lever or crank 44 the free end of which is connected by a link 45 to a pin 46 on one end of a rocking bar 47 mounted to rock on a suitably supported stud 48.

60 Each clearer support has a lug 27 that is acted on its underside by a spring pressed plunger 28, the spring 30 of which is contained in a housing 29 supported by the frame of the machine.

65 The ends of the rocking lever 47 are pro-

vided with set screws 51 that bear on the upper faces of the lugs 27 of the respective clearers (and by which the clearers and lugs 31 may be adjusted as may be required) the arrangement being such that when the workman changes the positions of the raceways 16, 17, as described, the mechanism just described will operate so that when the raceway 17 is connected up with the separator the right hand end of the rocking bar 47 will be 70 raised and consequently the lug 31 of the clearer in the tack-pot 9 will be thrown into the path of operation of the cam blocks 32 on that tack-pot, whereas the opposite or left hand end of the rocking bar will be depressed and by the action of the set screw 51 on the lug 27, the lug 31 of the clearer in the tack-pot 8 will be removed out of the path 75 of operation of the cam blocks on that drum. Obviously when the other raceway is moved 80 into communication with the separator 18 the clearer that has been in operation will be rendered inactive whilst the other will be put into operation.

The tacks separated off enter a raceway 19 90 in a raceway block 57 that is at a much greater inclination than the raceways 16, 17, so that the descent of the tacks will be accelerated.

In the apparatus illustrated by way of example, provision is made to deliver five tacks 95 to a tack machine—for example a pulling-over machine—in rapid succession from one or other of the raceways and for this purpose the apparatus includes the following mechanism which in the main is similar to that described in my former patent referred to, that is to say, the shaft 12 carries a chain wheel 64 and a chain 65 passes over this and over another chain wheel 66 mounted on a suitably supported shaft 67.

On said shaft is a disc 68 having five teeth or projections 69 all of which project an equal distance from the axis of the shaft. Mounted on a spindle 72 is a lever 71 that carries on one part a roll 70 and on another part a block 73, and the separator 18 is carried by a U-shaped part 76 which is fixed on a spindle 74 which is adapted to be reciprocated in bearings 75, 75, a spring being provided—for instance within the housing 77—to tend to maintain the spindle 74 (and the separator 18) in the extreme right hand position (Fig. 2). As the shaft 67 rotates the successive five teeth 69 will move the separator to the left whereas the spring will return the parts to normal position. By 110 these means five tacks will be divided off in 115 comparatively rapid succession.

These tacks slide down the raceway 19 and are to be received in flexible tubes 58, 59, 60, 61, and 62, and by these conducted to the appropriate tack driving devices of a pulling-over machine, but before entering the said flexible tubes it is desirable to invert the tacks because in modern practice pulling-over machines carry the shoe sole down and thus re- 120 125 130

quire the tacks to be driven upwardly into the work as is well understood.

In order to present the flexible tubes successively to the raceway 19 so as to receive the five tacks as these are successively separated I provide on the shaft 67 a cam disc 80 having five cam surfaces 81, 82, 83, 84, 85, which are at progressively greater distances from the axis of rotation of the shaft 67. On the spindle 72 I also mount a two armed lever 87 one arm 86 of which carries a cam roll to be acted on by the cam surfaces referred to and the other arm 87 of which engages a block that is provided with a stud 88 on a horizontally 15 slideable bar 63 to which latter the end of the flexible tubes 58 to 62 are connected, the arrangement being such that as the shaft 67 rotates the cam 80 will intermittently move the bar 63 towards the left and put the tubes 58 to 20 62 successively in communication with the raceway 19, so that they will receive the tacks previously separated after travelling the raceway 19.

As various lengths of tacks have to be dealt with, as already stated, I provide simple means for inverting these and the means comprise three studs or pins 52, 53, and 54, which are located at progressively different distances from the surface of the raceway 19.

30 If short tacks are being supplied the pin 54 will be engaged by the tacks as they travel down the raceway and this will suffice to bring about their inversion as is well understood. If, however, long tacks are being used, the pin 54 would strike the shank of the stud too high up and the inversion would not be or not always be brought about. I therefore provide the stud 52 which is at a much greater distance from the surface of the raceway 19 and will therefore engage the nail or tack near the end of its shank and thus cause it to be tilted; the next pin 53, being nearer the surface of the raceway will cause a further tilting of the nail until at last the stud 54 is 45 encountered when the nail will be completely inverted.

By this simple device a difficulty which has long been experienced, that is to say to invert tacks varying considerably in length without the use of complicated mechanism, is completely met.

Although I have described a constructional form of my invention which is adapted to deal with two kinds of tacks I wish it to be understood that I do not limit my invention thereto.

What I claim is:—

1. An apparatus for transferring tacks comprising a plurality of rotary tack pots, means to rotate said tack pots, a separator, raceways leading from said tack pots to said separator and adapted for alternate co-operation therewith, means to vibrate said separator, and means to engage short tacks at their 60 ends only and longer tacks first at their ends

and subsequently at their shanks to effect the inversion of said tacks.

2. In an apparatus for transferring tacks, in combination, two continuously rotating tack pots, a cam block on each tack pot, a raceway and a clearer within each tack pot, and means for operatively connecting either cam block with its respective clearer and simultaneously throwing out of action the clearer within the other tack pot. 70 75

3. An apparatus for transferring tacks comprising a plurality of rotary tack pots, means to rotate said tack pots, a separator, raceways leading from said tack pots to said separator and adapted for alternate co-operation therewith, and means for actuating said separator a plurality of times during 80 each cycle of operation of the machine.

4. An apparatus for transferring tacks, having in combination, a plurality of continuously rotating tack pots, a raceway and a clearer within each tack pot, said clearers being supported to swing about a pivot, means on each of said tack pot for imparting movement to its respective clearer, a separator, raceways leading from said tack pots to said separator and adapted for alternate co-operation therewith, and means whereby the movement of the raceways throws a clearer 85 into and another clearer out of action. 90 95

5. An apparatus for transferring tacks comprising a plurality of constantly rotating tack pots, a plurality of cams on each tack pot and rotating therewith, a clearer mounted for rocking movement within each tack pot and adapted for actuation by said cams, a separator, pivoted raceways leading from said tack pots to said separator and adapted for alternate co-operation therewith, and means whereby the movement of the raceways 100 105 brings a clearer within and removes another from the sphere of operation of said cams.

6. An apparatus for transferring tacks comprising a plurality of constantly rotating tack pots, a separator, raceways slidably supported within said tack pots, other raceways located outside of said tack pots and movable with respect to said tack pots and the separator, and yielding connections between the 110 raceways to hold the slideable raceways normally in engagement with the ends of the outer raceways. 115

7. In an apparatus for transferring tacks, a plurality of rotary tack-pots, pivoted raceways leading from said tack-pots, raceways slideable within the tack-pots, and means for holding said slideable raceways in engagement with the ends of the pivoted raceways. 120

8. An apparatus for transferring tacks comprising a plurality of constantly rotating tack pots, pivoted raceways leading from said tack pots, raceways slideable within the tack pots, and yielding connections between the pivoted and the slideable raceways. 125 130

9. An apparatus for transferring tacks having in combination two rotary tack-pots, means to rotate said tack pots, a separator, raceways leading from said tack pots to the 5 separator and adapted for alternate co-operation therewith, a plurality of nail receiving pockets, and means for imparting a plurality of movements to said separator and said pockets during each cycle of operation of the 10 machine.

10. In an apparatus for transferring tacks having in combination two rotary tack-pots, a pivoted raceway leading from each tack-pot, a separator, means to put either raceway 15 and the separator into active communication, a driven shaft, and a cam mounted on said shaft for actuating the separator a plurality of times during one rotation of said shaft.

11. In an apparatus for transferring tacks having in combination two rotary tack pots, a 20 slideable raceway and a clearer within each tack pot, a pivoted raceway leading from each tack pot, a separator, means to actuate the separator, a plurality of tack receiving 25 flexible tubes, and means for presenting said tubes successively in a tack receiving position.

12. In an apparatus for transferring tacks, 30 two constantly rotating tack-pots, a slideable raceway and a clearer within each tack-pot, mechanism to actuate the clearers, a member adapted for rocking movement and having two raceways therein adapted to communicate 35 respectively with the inner raceways, means to rock said member to render operative the appropriate raceway therein, and connections between said means and mechanism to render operative the appropriate 40 clearer and to throw the other clearer out of action.

13. An apparatus for transferring a plurality of either of two sizes of tacks having in combination two constantly rotating tack-pots, a slideable raceway and a clearer within 45 each tack-pot, means for actuating the clear-

ers, a pivoted raceway leading from and arranged for rocking movement relatively to each tack-pot, a separator, means to put either raceway in active communication with 50 the separator and simultaneously bring about the actuation of one and throw out of operation the other clearer.

14. An apparatus for transferring tacks comprising a plurality of constantly rotating tack pots, a separator, raceways arranged for rocking movement relatively to and leading from said tack pots to said separator and adapted for alternate co-operation with said separator, a cam to move said raceways, a 55 clearer for each raceway, means to actuate said clearers, and a second cam to control said clearers.

15. An apparatus for transferring tacks comprising a plurality of rotary tack pots, means to rotate said tack pots, a separator, raceways leading from said tack pots to said separator and adapted for alternate co-operation therewith, means to reverse the tacks 60 separated, and a series of pockets adapted to receive successively said tacks.

16. An apparatus for transferring tacks comprising a plurality of rotary tack pots, means to rotate said tack pots, a separator, 65 movable raceways leading from said tack pots to said separator and adapted for alternate co-operation therewith, a fixed raceway to receive the tacks when separated, a series of tack receiving pockets, and means to put said pockets successively in tack receiving 70 position with said fixed raceway.

17. An apparatus as claimed in claim 16 in which the tack receiving pockets are moved by successive steps to receive the tacks from 75 said fixed raceway.

18. In an apparatus for transferring tacks, a tack raceway inclined to the horizontal, and a plurality of studs located at progressively different distances from the surface of the raceway for progressively tilting the tacks 80 whilst travelling down said raceway.

CHARLES MARTIN BAGSHAW.
